MOBILE SUPPORT FOR CASKET LOWERING
EQUIPMENT

Harry H. Campbell, Kalispell, Mont.

Application May 14, 1948, Serial No. 27,091

10 Claims. (Cl. 214—77)

1

This invention relates to cemetery equipment and particularly to an improvement in mechanisms comprising a mobile support for equipment for lowering caskets.

Casket lowering apparatus is now generally employed for the purpose of lowering caskets vertically, evenly and at a uniform rate into deeply dug graves. A conventional apparatus of this type comprises a rectangular frame which includes four corner posts and elongated longitudinal and transverse members rigidly connecting the corner posts, the apparatus also including two parallel elongated rotatably supported members about which the casket supporting bands are initially wound and means for permitting these members to rotate slowly and at uniform speed under the weight of the casket so as to pay out the casket supporting bands at a uniform rate and ensure proper descent of the casket. While apparatus of the character just above briefly described are in widespread use, no satisfactory means has heretofore been devised whereby such an apparatus may be transported from a point of storage to a point of use, properly positioned at the graveside, and again lifted and returned to storage, without the expenditure of considerable time and effort on the part of a number of attendants.

The present invention contemplates the provision of a novel assembly of frame and mobile support which may be readily removed from storage by a single attendant, the frame properly positioned at the graveside and returned to storage after it has been used, all in a minimum time and with minimum effort. The casket lowering frame of the assembly is constructed in such manner that it may be conveniently engaged, lifted, lowered and transported by the mobile support, and a mobile support is designed and constructed in such manner as to enable it to function most efficiently in the lifting, lowering and transportation of the frame. Such support comprises a structure mounted upon wheels rotatable about a common axis, the support being tiltable from a horizontal to a vertical position and being used, in the elevation and lowering of one end of the frame, in the manner of a lever, having arms which are unequal in length so that the operator can lift the end of a heavy frame with but slight effort. The mobile support may, after one end of the frame has thus been lifted from the ground and while the other end is still at rest on the ground, move the mobile support beneath the frame, an interposed anti-friction device permitting this operation to be done with

2

the expenditure of very little effort. Finally, when the mobile support has been moved into a predetermined position beneath the frame it may be, by a slight tilting movement, caused to engage the frame at additional points of support, there being preferably three such points altogether and, by a slight further tilting movement, the entire frame lifted from the ground, whereupon the assembly may be moved freely and easily.

It will be appreciated that the details of design and arrangement of the parts of the two members of the assembly, i. e. the frame and mobile support, may be considerably modified without loss of advantage but in every instance the frame will include means to be engaged by the support while the support is being operated as a lever to lift or lower the frame end, and the same or different means to continuously engage an elongated member or trackway on the support as the support is moving under the frame or is being withdrawn. That form of the invention which is illustrated and now to be described in detail is set forth by way of example.

25 In the drawings:

Figure 1 is a top plan view of the mobile support;

Figure 2 is a perspective view of the same;

Figure 3 is a section on line 3—3 of Figure 1, the frame being shown in dotted lines in the position which it normally occupies upon the mobile support when the assembly is ready for transportation;

Figure 4 is a side elevation of the frame and 35 mobile support, these portions of the assembly occupying the relative positions in which they are disposed just prior to actuation of the support to elevate the end of the frame;

Figure 5 is a similar side elevation showing in 40 full lines the frame and support in the positions which they respectively occupy after the support has been operated as a simple lever to elevate the end of the frame; the relative positions of the frame and support, after the support has been partially moved under the frame, being illustrated in dotted lines in this figure;

Figure 6 is a side elevation of the assembly, ready for transportation;

Figure 7 is a perspective view, on a somewhat 50 larger scale, of a detail of the invention; and

Figure 8 is a perspective view of a similar detail of a modified form of the invention.

The automatic casket lowering mechanism, hereafter designated the frame, is indicated at C and the mobile support is generally indicated at S.

The frame includes parallel elongated side members, one of which is illustrated at 10, parallel transverse members 11, four corner posts 12 to which the ends of the members 10 and 11 are rigidly secured, and parallel side shafts 13 the ends of which are rotatably supported within the housings 14 mounted upon the corner posts 12. The shafts 13 are connected by the casket supporting bands 15, the ends of which are wrapped around the shafts respectively, and the arrangement is such that a casket placed centrally upon bands 15 will be allowed to descend into a grave under the close control of an operator who, by manipulating mechanism which is not illustrated but which is well known in the art, will permit shafts 13 to slowly rotate at identical speeds and pay out each band in equal increments from opposite sides of the grave.

The details of construction of the frame or automatic casket lowering mechanism form no portion of the present invention and are for that reason not specifically described. It has at each end a transversely extending bracing member 16, disposed below the brace 11 previously referred to and upon one such transverse brace, as may be most clearly seen in Figure 7, is affixed a bracket 18 which carries a grooved roller 19. Roller 19 comprises an anti-friction device which facilitates relative longitudinal movement of frame and mobile support in assembling or disassembling these two major elements of the invention.

The mobile support includes an axle 20 disposed horizontally and upon the ends of which are rotatably mounted suitable wheels 21 preferably equipped with pneumatic tires. Disposed at right angles to the axle 20 and extending forwardly from the mid-point thereof is an elongated structural member or tongue 22, preferably tubular, the end of this member being preferably welded to the axle. At its forward end the member is provided with a hook 23 by means of which the mobile support may, if desired, be attached to another vehicle but which, when not so used, may conveniently be grasped by an operator. Extending upwardly from the mid-point of axle 20 are two tubular elements 25 and 26 which comprise supports for the rear end of the elongated tubular or rod-like frame engaging member 28. The forward end of member 28 is secured, preferably by welding as at 29, to the main frame member or tongue 22. One end of member 28 is provided with an upwardly extending curved or hook-like portion 28a of reduced section and, adjacent its other end, there is located a rigid stop 30, the upper surface of member 28 between the hook-like terminal portion 28a and stop 30 comprising a runway or track for the grooved anti-friction roller 19 mounted upon the end of the frame.

The mobile support also includes suitable additional bracing members including the transverse structural element 32 disposed in advance of the axle 20 and parallel thereto, connecting elements 33, and diagonal brace rods 34 extending forwardly from member 32 and the ends of which are welded to the tongue 22. Disposed above axle 20 is a horizontally disposed frame supporting rod 36 the ends of which are rigidly attached to vertically disposed supporting members 37 and 38 and the mid-point of which is supported by the upright bracing member 25. The upper end of each of the bracing elements 37 and 38 is outwardly turned and is connected to a bracing element disposed radially of the adjacent wheel and

the lower end of which is mounted upon the axle of the wheel, these bracing elements being indicated at 37a and 38a, respectively. Horizontal braces 40 and 41 connect the ends of the wheel axle respectively to the ends of transverse rod 32.

The details of construction of the mobile support may be considerably varied but in every instance the support will include a member such as member 28 which provides an elongated track-way or runway for an anti-friction roller. In each embodiment, also, the hook 28a or its equivalent will be disposed relatively close to the axle 20, the support as a whole thus comprising a lever having a short arm the length of which is equal to the distance between the axle 20 and the hook 28a, and a relatively long arm the length of which is equal to the distance between the axle 20 and the hook 23, the support when used as a lever thus providing the operator with great mechanical advantage.

Normally, and while the assembly is in storage, the frame will be superposed upon the support. Actually the frame has direct contact with the support at three places, its elongated side members 10 engaging and resting upon the transverse member 36, the points of contact being adjacent the outer ends of member 36, and the roller 19 engaging member 28 just in rear of the stop 30, the roller resting against the stop. Thus the frame is mounted upon the support firmly at three points and may not tilt or slide. Preferably the cross member 36 is provided with rubber cushioning sleeves 43 and it is upon these sleeves 43 that the elongated frame members 10 of the frame rest.

If it be assumed that the frame of the apparatus has been used in the lowering of a casket and is to be removed for storage, the mobile support will be wheeled into the position in which it is illustrated in Figure 4, being disposed in such manner that the tongue 22 extends in a substantially vertical direction, the hook-like end 28a of member 28 being then disposed beneath the roller 19 of the frame. The entire support may then be rocked about its supporting axle in a clockwise direction, into the position in which it is shown in full lines in Figure 5 the adjacent end of the frame being thus elevated well above the ground. The mobile support may then be advanced or thrust beneath the frame, one end of which engages the ground, the roller 19 rolling along the upper surface of the moving roller support 28 and maintaining a single point of contact between the support and the elevated end of the frame. This forward movement of the support is continued, through the dotted line position in which it is shown in Figure 5, until the roller 19 reaches the stop 30, thus preventing further movement, the wheels 21 being so spaced apart that they will be upon opposite sides of a grave opening of standard width about which the frame is centered. After roller 19 has made contact with stop 30 and forward movement of the support is thus arrested, the operator will depress the forward end of the tongue 22 and thus bring the cross bar 36 upwardly into contact with parallel elongated members 10 of the frame and, upon slight further depression of the tongue 22, the cross bar will lift the frame entirely from the ground, or to the position in which it is shown in Figure 6. The assembly is then ready for transportation and may be readily drawn by a single attendant even over a difficult terrain, to a point of storage.

When the apparatus is brought from storage

to be used the procedure thus described will be reversed, the mobile support being tilted until one end of the frame engages the ground, as in Figure 5, the support being withdrawn until the roller 19 is in engagement with the hook-like extremity 28a of member 28 and the support then allowed to tilt into vertical position as shown in Figure 4, whereupon the frame is fully positioned and the support may be withdrawn and removed from the vicinity.

It may be desirable to provide the support with two parallel roller engaging members to give increased stability, such a mechanism being illustrated in Figure 8. Here the parallel roller supporting members are designated 46 and there will likewise be two anti-friction rollers 47 included in the anti-friction device, these rollers 47 being mounted upon an axle 48 the ends of which are fixed in parallel portions 49 and 50 of the bracket B which is mounted upon end member 11. Other minor changes may readily be effected if desired.

Having thus described the invention, what is claimed as new and desired to be secured by Letters Patent is:

1. Casket lowering mechanism comprising a rectangular frame and a mobile support therefor, the assembly being tilttable about a horizontal axis to bring one end of the frame into contact with the ground and including anti-friction means between frame and support to facilitate movement of the support relative to the frame when the end of the frame is in contact with the ground.

2. Casket lowering mechanism comprising a rectangular frame and a mobile support therefor, the support being tilttable to bring the frame into inclined position with one end thereof in contact with the ground, anti-friction means interposed between frame and support comprising the sole contact therebetween when the support has been tilted and the end of the frame has been brought into contact with the ground, whereby the support may be freely withdrawn from beneath the frame.

3. Casket lowering mechanism comprising, in combination, an elongated frame and a tilttable wheeled support therefor, said frame having an anti-friction device at one end and the support having means to engage said anti-friction device to facilitate raising and lowering of that end of the frame and movement of the support longitudinally of the frame.

4. Casket lowering mechanism comprising, in combination, a frame and a mobile support therefor, the support being tilttable about a horizontal axis, and means on the support for engaging the frame at one end, lifting that end when the support is tilted, and maintaining said end elevated as the support is moved under the frame.

5. Casket lowering mechanism comprising, in combination, a frame and a mobile support therefor, the support being tilttable about a horizontal axis, and means on the support for engaging the

frame at one end, lifting that end when the support is tilted, and maintaining said end elevated as the support is moved under the frame, said means including an elongated member disposed at right angles to the axis about which the support is tilttable.

6. Casket lowering mechanism comprising, in combination, a frame and a mobile support therefor, the support being tilttable about a horizontal axis, and means on the support for engaging the frame at one end, lifting that end when the support is tilted, and maintaining said end elevated as the support is moved under the frame, said means including an elongated member having a hook at one end to engage the frame, said member being disposed at right angles to the axis about which the support is tilttable.

7. The combination set forth in claim 6 in which the frame is provided with anti-friction means to engage said member.

8. The combination set forth in claim 6 in which said support is provided with members to engage the sides of the frame to provide three points of contact between frame and support.

9. Casket lowering mechanism comprising, in combination, a rectangular frame, a wheeled support tilttable about a horizontal axis, said support having three point engagement with said frame when the support is disposed for movement of the assembly and having one point engagement when the support is tilted to bring one end of the frame into contact with the ground.

10. Casket lowering mechanism comprising, in combination, a rectangular frame, a wheeled support tilttable about a horizontal axis, said support having three point engagement with said frame when the support is disposed for movement of the assembly and having one point engagement when the support is tilted to bring one end of the frame into contact with the ground, the single point of engagement being provided by an anti-friction device mounted on said frame and an elongated member on said support engaging said device.
